UNITED STATES PATENT OFFICE.

EDWARD C. SEYMOUR, OF DETROIT, MICHIGAN, ASSIGNOR TO THE ALUMINUM PLATE AND PRESS COMPANY, OF NEW YORK, N. Y., AND PLAINFIELD, NEW JERSEY.

SHEET-COUNTING DEVICE FOR PRINTING-PRESSES.

SPECIFICATION forming part of Letters Patent No. 657,792, dated September 11, 1900.

Application filed May 22, 1900. Serial No. 17,567. (No model.)

To all whom it may concern:

Be it known that I, EDWARD C. SEYMOUR, a citizen of the United States, residing at Detroit, in the county of Wayne and State of Michigan, have invented certain new and useful Improvements in Sheet-Counting Devices for Printing-PresSES, of which the following is a full, clear, and exact description.

Sheet-counting devices for printing-presSES are usually arranged adjacent to the delivery end of the machine and operatively connected with the delivery-fly, so that every time a sheet is thrown over upon the receiving-platform by the fly the counting mechanism registers it. With such an arrangement the counting mechanism is positively connected with the sheet-delivery fly, and it will be clear that every movement of the fly into delivery position will be registered upon the counting mechanism whether or not a sheet is delivered. This is, in fact, true of any arrangement of the counting mechanism in which a constantly-operating part of the press is positively connected with the counting mechanism. Such arrangements are objectionable, because they give an inaccurate count of the sheets printed and really indicate only the number of movements made by the part of the press to which the counting mechanism is connected.

The object of my present invention is to produce a counting mechanism which will accurately indicate the number of sheets actually printed irrespective of the number of revolutions made by the press; and to this end my invention comprises suitable counting mechanism, suitable throw-out mechanism for moving the impression-surface into and out of operative relation to the plate or form surface, means operating the counting mechanism through one of the operating parts of the press, and means connecting the counting mechanism with said throw-out mechanism, whereby the counting mechanism will be moved out of operative relation to its operating mechanism when the impression-cylinder is thrown away from the plate or form surface, and will be thrown into operative relation with its operating mechanism when

the impression-surface is moved into operative relation with the form or plate surface. With such an arrangement it will be clear that the counting mechanism can be actuated only when the parts of the press are in position to make an impression upon a sheet, and that when the parts of the press are moved into inoperative position, although they may continue to move, the counting mechanism cannot be actuated, and hence it is impossible to make an inaccurate count of the impressions made.

In the preferred construction of my improved counting mechanism I have applied my invention to a rotary cylindrical press, the impression-cylinder of which is journaled in eccentric bearing-bushings which are capable of limited rotary movements for moving the impression-cylinder into and out of operative relation to the plate or form cylinder. In this preferred construction I mount the counting mechanism in a suitable bracket upon the press-frame, so that it will be capable of movement in its support, and I connect it by means of a suitable link with one of the eccentric bearing-bushings of the impression-cylinder, the operating-arm of the counting mechanism being arranged to be actuated by a pin or lug mounted upon a flange or collar supported upon the projecting shaft of the impression-cylinder. With this arrangement it will be clear that when the eccentric bushings are rotated to move the impression-cylinder out of operating relation to the plate-cylinder, the counting mechanism will be moved backwardly away from the impression-cylinder shaft, so as to carry the operating-arm out of the path of the pin or lug carried by the flange or collar on the cylinder-shaft. In the reverse operation when the impression-cylinder is moved into operative relation with the plate-cylinder it will be clear that the counting mechanism will be drawn toward the impression-cylinder shaft, so as to bring the operating-arm of the counting mechanism into the path of the operating pin or lug.

In order that my invention may be fully understood, I will first describe the same with

relation to the accompanying drawings and will afterward point out the novelty more particularly in the annexed claims.

In said drawings, Figure 1 is a side elevation of part of a printing-press having my improved counting mechanism applied thereto, the parts being shown in operative position. Fig. 2 is a similar view showing the parts in inoperative or throw-out position.

10 1 indicates a part of the press-frame of a rotary printing-press.

12 2 is the plate or form cylinder, journaled in frame 1.

14 4 is the impression-cylinder, mounted upon the shaft 5, which is journaled in eccentric bearing-bushings 6, said bushings 6 being in turn journaled in the machine-frame 1 and formed with integral arms 7, which are connected with any suitable operating mechanism, such as toggle-links 8 9, by which they are operated for moving the impression-cylinder into and out of operative relation with the plate or form cylinder,

16 10 is a counting device of any approved construction. This device is mounted to slide in a bracket 11, secured to the press-frame 1 and formed with guide-flanges 12 for confining the counting device therein and at the same time allowing it a longitudinal sliding motion.

18 13 is a link pivoted at one end 14 to the counting device 10, and at its other end 15 to one of the eccentric bearing-bushings 6 in which the impression-cylinder is journaled.

20 16 is the operating rock-arm of the counting mechanism, suitably connected with the internal operating mechanism of the counting device 10, so that every complete stroke of the arm 16 will register one number in the counting device. The operating-arm 16 may

25 be of any suitable construction, but is shown as formed with two parts, having a knuckle-joint at 17 and a spring 18, mounted upon one of the parts and engaging the other, so that when the arm 16 is moved downwardly it will register on the counting mechanism; but when there is a tendency to move it upwardly beyond its normal position by external force it will break joint at 17.

30 20 is a collar adjustably mounted upon the projecting end of the impression-cylinder shaft 5 by means of a set-screw 21. The collar 20 supports a pin, lug, or screw 22, which in its rotation engages the counter-operating arm 16 and registers the revolution thereon.

35 It will be observed from the above description and the accompanying illustrations of my improved counting mechanism that when the impression-cylinder is thrown into inoperative position—that is, away from the plate or form-cylinder, as shown in Fig. 2 of the drawings—the counting device 10 will move away from the impression-cylinder shaft 5, so as to move the counter-operating arm 16 out of the path of the pin, lug, or screw 22, so that even though the cylinder continues to rotate the counter will not be operated. From

Fig. 1 it will be observed that when the impression-cylinder is moved into operative relation with the plate or form cylinder the 70 counter-operating arm 16 will rest in the path of the operating pin, lug, or screw 22, so as to register every rotation.

The specific construction of the counter-operating arm 16, as above described, forms no 75 part of my present invention, but is the invention of Jerome W. Leary, who has made application for patent thereon, serial number of same being 19,108, filed June 5, 1900. The object of the knuckle-jointed operating-arm is to avoid breaking the arm or the counting mechanism when the impression-cylinder is backed up or rotated backwardly while the counter is in operative relation to it, and also to permit throwing out of operation the counting mechanism while the press is printing the “dead sheets” or first lot of sheets which are run through to properly test the register, the inking, and the general operation of the press.

80 With my improved sheet-counting mechanism above described I am able to obtain an accurate count of the actual number of sheets printed, for the reason that the press-operator feeds a sheet into the press at every revolution while the cylinders are rotating in 85 operative relation, and the moment he finds that for any reason he will be unable to get a sheet into position to be taken by the impression-cylinder he operates the throw-out mechanism, so as to prevent the soiling of the 90 impression-surface by making an impression thereon, and this operation moves the counting device out of operative relation with its operating device. In this way the counting device is operated while the press is printing 95 and is not operated while the press is not printing.

Having thus described my invention, what I claim as new therein, and desire to secure by Letters Patent, is—

100 1. The combination with the form and impression cylinders of a printing-press, and means for moving the impression-cylinder into and out of operative relation with the form-cylinder, of a counting device, means 105 rotating with a moving part of the press for operating the counting device and means connecting the counting device with the impression-cylinder-throw-out mechanism, whereby the counting device will be moved 110 out of operative relation with its operating mechanism when the impression-cylinder is thrown out of operative position, and vice versa, substantially as and for the purpose set forth.

115 2. The combination with the form and impression cylinders of a printing-press, and suitable throw-out mechanism for the impression-cylinder, of a collar mounted upon the impression-cylinder shaft, a pin or lug carried 120 by said collar, the counting device having an operating-arm which is adapted to be engaged by said pin or lug, and a link connecting the counting device with the throw-out mechan-

ism, whereby it will be moved toward and away from the impression-cylinder shaft, substantially as and for the purpose set forth.

3. The combination with the form and impression cylinders of a printing-press, suitable eccentric bearing-bushings in which the impression-cylinder is journaled, and means for operating said eccentric bushings for moving the impression-cylinder into and out of operative relation with the form-cylinder, with a counting device movably mounted in

a suitable support, a link connecting the movable counting device with one of said eccentric bushings, an operating-arm for the counting device, and a part rotating with the impression-cylinder and adapted to actuate said operating-arm, substantially as and for the purpose set forth. 15
